UNITED STATES PATENT OFFICE.

THOMAS C. HANSEN, OF CANEY, KANSAS.

PIN FORM FOR CROWNS AND THE LIKE.

Application filed April 28, 1925. Serial No. 26,479.

To all whom it may concern:

Be it known that I, THOMAS C. HANSEN, a citizen of the United States, residing at Caney, in the county of Montgomery and 5 State of Kansas, have invented certain new and useful Improvements in Pin Forms for Crowns and the like, of which the following is a full, clear, and exact description.

Porcelain crowns, such as the S. S. White, 10 Justi, Twentieth Century, Davis, Goslee, etc., are usually mounted on the tooth root by means of pins of base metal which are furnished with the crown. Considerable trouble is incurred in attaching these crowns 15 to the teeth, for the reason that the metal pin is weakened by overheating when the cope is cast thereon. Furthermore, an excessive amount of gold was used, for the reason that the wax cope became hopelessly 20 distorted unless made of substantial thickness. And, again, it was practically impossible to cast a thin cope to a metal pin, due to the fact the metal of the pin cooled the molten metal and caused an imperfect casting. 25

An object of the present invention is to overcome the foregoing objectionable features in fitting crowns, inlays, etc., by providing a thin cope and hollow pin of celluloid or similar combustible material which 30 may be readily conformed to the root and crown and then burned out and cast in the usual manner.

Another object of the invention resides 35 in the provision of a pin such that the same may be readily engaged and removed by means of the sprue, and also in the provision of a pin which, though of normal size, yet contains a minimum of material, there- 40 by practically eliminating distortion to the investment when the mold is burned out or exploded.

A further object of the invention con- 45 sists in the provision of hollow celluloid pins or tubes to be employed generally in casting operations in dentistry, whether it be lingual bars, crowns, inlays, bridge work or other construction peculiar to the dental art.

50 Other objects and advantages of the invention will be apparent from the following description when taken in connection with the accompanying drawings, in which:

55 Figure 1 is an enlarged perspective view of the hollow celluloid pin and cope attached.

Figure 2 is a view similar to Figure 1, showing the wax attached.

Figure 3 is an enlarged perspective view 60 of a slightly modified form of pin.

Figure 4 is a sectional view of a mold with pin and cope in position.

Figures 5 and 6 are side elevations and 65 sections respectively of a pin employed in connection with an inlay.

Figures 7 and 8 are side elevations and 70 sections respectively of a finished pin crown.

Figures 9 and 10 are sectional views of a pin and cope as applied to a porcelain dum- 75 my to be used in bridge work or the like.

Figure 11 is an end view of a lingual bar, and

Figure 12 is a side elevation of a tube to be used in casting lingual bars.

It should be noted that the various figures 75 of the drawing are merely illustrative of a few of the many uses to which my invention may be put, and that it is, therefore, not my intention to be limited to the specific em- 80 bodiments shown, except in so far as such ap- pended claims.

Referring to the drawing more in detail, and more specifically to Figures 1, 2, 4, 5 and 6, the numeral 1 indicates a hollow pin 85 of celluloid or similar combustible mate- 90 rial to which is attached a relatively thin celluloid cope 2. When fitting this construc- 95 tion to a root to be crowned, wax 3 may be applied to the upper or lower surface of the cope 2, as found desirable, and the ends of the pin closed by wax 4. The crown is then removed and a sprue 5, as indicated in Figure 6, is attached to the wax 4 in the outer end of the pin for the purpose of removing 100 the pattern and placing the same in the mold 6, Figure 4. The mold is then burned out in the usual way and the molten metal poured in to form the casting.

In Figure 3 I have shown a celluloid pin 7 100 which is similar in all respects to the disclosure in Figures 1, 2, 4, 5 and 6, except for the corrugations 8, which may be employed where it is desired that the pin be more firmly cemented to the root.

In Figures 5 and 6 the pin form 1 is em- 105 ployed in connection with inlays, the numer- al 9 indicating the wax molded into the cav- ity and around the celluloid pin form.

The completed crown and pin are indicated by the numerals 10 and 11, respective- 110 ly, Figure 8, while numeral 12 indicates a

porcelain dummy to which the flanged celluloid pin 13 may be fitted. A still further form is shown in Figure 10, in which the pin form 1 is fitted to the porcelain dummy 14.

5 In Figure 11 I have shown a completed lingual bar 15, and in Figure 12 is shown a celluloid tube 16 filled with wax 17. In using this form of the invention the tube 16 may be heated and manipulated to the desired shape and then chilled.

In accordance with the patent statutes, I have described what I now believe to be the best embodiment of the invention, but I do not wish to be understood thereby as limiting myself or the scope of the invention, as 15 many changes and modifications may be made without departing from the spirit of

the invention; all such I aim to include in the scope of the appended claims.

What I claim as new and desire to secure 20 by Letters Patent is:

1. A pattern to be used in casting dental work, including a hollow pin of combustible material.

2. A pattern to be used in casting dental 25 work, including a hollow celluloid pin.

3. A pattern to be used in casting dental work, including a hollow pin and cope of combustible material.

4. A pattern to be used in casting dental 30 work, including a hollow pin and cope of celluloid.

THOMAS C. HANSEN.
